CONTAINER AND METHOD OF CLOSING THE SAME

Henry T. Scott, Toledo, Ohio, assignor to American Sealcone Corporation, New York, N. Y., a corporation of New York

Application October 15, 1936, Serial No. 105,704

3 Claims. (Cl. 229—1.5)

This invention relates to containers made of suitable material, such as paper and the like, particularly adapted for the distribution of milk and other liquids, and while the invention is applicable to containers of different forms and structures it relates particularly to containers including a side wall or body portion with closure means at one end to constitute the bottom of the container, and the opposite end constituting the 5 filler opening closed by moving or pressing together opposite wall portions of said end of the container which are secured and sealed in said condition, as shown in Patent No. 1,699,549.

In this method of closing and sealing the filler 10 end of the container great difficulty has been experienced in providing not only a liquid tight seal between the closure means and container but to maintain such seal, since the seal is readily broken, with a consequent leakage of the contents from the container, by strains and stresses transmitted to the closed filler end and by forces applied to the container from within or outside of the container. Furthermore, in packing containers of this character in cartons or crates for 15 storage or shipping, containers are first assembled in the carton or crate in rows in upright position supported from the bottom end and then containers in inverted position are engaged between adjacent containers of a row of containers to be supported at the closed filler end and at opposite wall portions thereof from the sides of the containers supported at the bottom end with the result that not only is the weight of the contents of such inverted containers supported at the closed 20 filler end which tends to cause said end of the containers to collapse, but the weight of the contents in the containers exerts a stress and strain upon the pressed-together wall portions of the containers that tends to spread apart such pressed-together portions with a consequent 25 opening of the container and leakage of the contents therefrom.

It is an object of the invention to provide an improved container to overcome the above disadvantages and an improved method of closing the filler end of the container, whereby when the filler opening is closed the closure parts add rigidity to and reinforce said end of the container and when sealed in closed condition maintain the closure parts in closed condition and prevent a change in the form of the closure parts that will break the seal during the handling of the container, and arrange the closure parts whereby one of said closure parts will support the other part thereby not only forming a particularly

strong closed end, but one part will exert a closing force on the other of said parts of the container and retain the same in closed condition.

It is another object of the invention to provide a container having a straight-line side wall or 5 body arranged with closure means at one end to constitute the bottom of the container, and provide an improved method of closing the opposite end constituting the filler opening of the container by pressing together opposite wall portions at said end and arranging said closure portions in arcuate shape transversely of the container and adapting the inner portion of said pressed-together portions to serve as a truss to the outer portion and add rigidity to and reinforce 10 said end of the container, and adhesively bonding said closure parts together to seal the same.

It is another object of the invention to provide a container of this character wherein the 20 parts of the container are secured together by a thermoplastic adhesive material by providing a blank adapted to be shaped to and constitute the container body, and prior to forming the container body, with a thermoplastic adhesive material; whereby a portion of the blank that is 25 adapted to be lapped over another portion to form the side seam of the container body, the part to contact the closure member for the one end of the container, as well as wall portions constituting the closure parts at the filler end that are 30 pressed together and contacted, are adapted to be adhesively bonded together under pressure and an elevated temperature.

Still another object of the invention is to provide a container which may be manufactured, packed, closed and sealed in an economical manner substantially entirely by automatic machinery, which requires a minimum of material, which may be constructed of a relative light and thin 35 material and at the same time be strong, durable 40 and leakproof, and provide a single service container that is tamperproof.

The invention relates to a container wherein the side wall or body is constructed of a blank 45 shaped to form the body of the container and a closure member is secured in one end of the body to constitute the bottom of the container and the opposite end to constitute the filler opening closed by pressing together opposite wall portions 50 at said end of the container, and it is a further object of the invention to provide an improved construction and arrangement of blank for a container body whereby when the filler opening 55 of the container is closed the edges of the closure

parts will extend in the same plane substantially parallel to the bottom of the container.

Other objects of the invention will appear from the following description taken in connection with the drawing forming a part of the application, and in which Figure 1 is a perspective view of a container embodying the present invention and showing the same with the filler opening closed.

- 5 10 Figure 2 is a plan view of a blank to form the container body arranged with a strip of thermoplastic adhesive material disposed relative to a side and the opposite ends of a surface of the blank.
- 15 20 Figure 3 is a side elevation of the end of the container with the filler opening the body of which is constructed from a blank as shown in Figure 2 and showing the relation of the edge of opposite wall portions of the container prior to pressing said parts together to close the filler opening of the container.

25 Figure 4 is a plan view of members movable toward and away from each other between which the filler end of a container is adapted to be engaged and adapted to be closed by the movement of said members toward each other and subjected to pressure and an elevated temperature to seal the same and simultaneously longitudinally fluting the closed and sealed portions 30 and showing the same in container-closing and sealing position.

35 Figure 5 is a cross-sectional view of the container-closing and sealing members taken substantially on the line 5—5 of Figure 4 looking in the direction of the arrows.

40 Figure 6 is a view similar to Figure 5 but showing the container closing and sealing members in spread position and the end of a container with the filler opening engaged between the same preparatory to closing and sealing the same.

45 Figure 7 is a longitudinal sectional view of the upper portion of the container shown in Figure 1 and taken substantially on the line 1—7 of Figure 1 looking in the direction of the arrows and showing the relation of the pressed-together and sealed parts; and Figure 8 is a detail view in section to show the manner of securing a bottom closure in the body.

50 In carrying out the embodiment of the invention illustrated in the drawing there is provided a died-out blank B cut from a sheet or web of the material from which the container is to be made, and from which blank the body or side wall of the container is constructed by 55 shaping the same to tubular form about a mandrel or horn with a marginal portion of one side lapped over and adhesively secured to a marginal portion at the opposite side under pressure and an elevated temperature for which purpose the blank is provided, as shown, with a strip 8 of thermoplastic adhesive material. As shown the blank is adapted to form a container body of truncated conical form in which a closure is adapted to be secured in the end of larger diameter to constitute the bottom of the container, and the opposite end to constitute the filler opening of the container closed by pressing together opposite wall portions to lie in contiguous relation and secured in said condition. For this purpose, as shown in Figure 2, there is provided a blank of quadrilateral form. The opposite longitudinal side edges of the blank 9, 10 converge at the same angle from one end to the opposite end of the blank, the edge of the blank between the diverging ends of the side edges being of convex

arcuate form and consisting of an arc of a circle whose center lies in a line extending vertically or perpendicularly to said arcuate end and substantially centrally between the terminals of said edge of the blank. The blank at the juncture 5 of said arcuate edge with the side edge 10 is cut away on an obtuse angle to said side edge 10, said cut away portion being of a width equal to the width of a marginal portion at said side of the blank, as indicated by the dot and dash line 11, 10 to be overlapped by a marginal portion at the opposite side of the blank, as represented by the dot and dash line 12, in securing the blank together to form the container body.

15 The edge of the blank of the portion of less width between the converging ends of the side edges of the blank is of reversely curved or sinuous form, the successive arcuate portions of which edge are in an arc of a circle having the same radius and a radius greater than the convex curved edge of the blank, and extending from one side edge, as the edge 10, to the opposite edge 9. One of said edge portions 14 is of concave form and extends between the longitudinal side edge 10 and a dot and dash line 13 to constitute one-half of the side wall of the container body. The successive reversely curved portion 15 extends between the dot and dash lines 13 and 12 substantially equal in length to and constituting the opposite side wall of the container 30 body, being of convex form, and the successive curved portion 16 extending between the dot and dash line 12 and the side edge 9 of the blank, constituting the overlapping portion of the blank, 35 being of concave form. The thermoplastic adhesive surface 8 as shown is substantially equal in width to the overlapped portion, and as shown correspondingly formed strips 8', 8'' of thermoplastic adhesive material are disposed at the top and bottom marginal portions of the blank for a 40 purpose hereinafter described. The radii of the arcuate portions 14, 15 and 16 are approximately one-third greater than the radius of the arcuate edge between the converging ends of the side edges of the blank at the opposite end of the 45 blank. In shaping the blank to tubular form the side marginal portion with the adhesive surface 8 is lapped over the opposite marginal portion to an extent substantially equal to the width between the edge 10 and the dot and dash line 11 50 and subjected to pressure and an elevated temperature to render the thermoplastic adhesive material 8 viscous and cause the surfaces to be bonded together. In the end of larger diameter of the container body so formed there is inserted a flanged bottom disk preferably of a somewhat stiffer material than the material of the blank, although this is not absolutely essential, with the flange of the disk extending outwardly and lying contiguous to the inner surface 60 of the container body within the adhesive surface 8'' and said bottom disk secured in the body by rolling the end of the body and disk flange upon themselves, preferably inwardly as shown in Figure 8, under pressure and an elevated temperature, although the same may be subjected to an elevated temperature after said portions are rolled together, to render the thermoplastic adhesive material viscous and cause the contiguous surfaces of the container body and bottom disk 65 to be bonded together.

70 In a container so formed the edge 15 at the filler opening and extending for substantially one-half the circumference of the container body from the juncture of said edge with the over- 75

lapped marginal portion will be arranged of upwardly extending convex form while the opposite edge portion 14 will be arranged to downwardly extending concave form, as shown in Figure 3. In this condition of the container, to close the filler opening the container is positioned so that the portion with the arcuate edge 15 between the dot and dash lines 12, 13 is in opposed relation to the portion with the arcuate edge 14 between the side edge 10 and the dot and dash line 13 with the portion at the arcuate edge 16 overlapping the marginal portion 10. When the portion with the arcuate edge 15 is pressed and moved toward the portion with the edge 14, thereby causing the intermediate portion of the edge 15 to be displaced downwardly relative to the opposite end portions thereof, and the intermediate portion of the edge 14 to be moved upwardly relative to the end portions thereof so that as the adhesive surface of said portions are brought into contact, said edges 14, 15 will extend in the same plane substantially parallel to the bottom of the container, as shown at 17 in Figures 1 and 5. In said condition they are subjected to pressure and an elevated temperature to render the thermoplastic adhesive material viscous and cause a bonding together of said wall portions and sealing of the closed filler opening. By this method of collapsing or pressing together said portions the side edge 10 at the closed end is at one end of the closed container end, as at 18 in Figure 1, in abutting relation with the fold of the marginal portion 9 effected by the pressure. The side edges of the blank in the open condition of the container extend substantially in a straight line for the full length of the container body, and when the filler opening is closed are caused to assume a spiral form in the longitudinal direction thereof which causes the marginal portion 9 to exert a force in an inward direction toward the marginal portion 10, and the marginal portion 10 to exert a force in an outward direction toward the marginal portion 9 and thus hold the marginal portions 9, 10 in firm contact with each other. As the portion of the container with the arcuate edge 15 is pressed and moved toward the portion with the arcuate edge 14 of the portion of the container between the ends of the arcuate portion 15 is caused to assume concave form and extending in a direction longitudinally of the container, as shown at 19 in Figure 1, which concave portion not only serves to truss said end of the container but also the opposed portion of the container wall adjacent the arcuate edge 14; and the two portions co-operate to truss each other not only add rigidity to but also reinforce the filler end of the container. To further reinforce the closed filler end the portions adhesively bonded together are interlocked, which is effected by laterally offsetting said portion and longitudinally fluting the same, and as shown at 20 offset laterally from the convex toward the concave side; but it will be obvious that it may be offset in the opposite direction and produce the same result.

In Figures 4, 5 and 6 there is shown means for carrying out the method of closing and sealing the filler opening of the container, comprising a pair of heads 21, 22 supported to have movement away from and toward each other and when moved away from each other or spread permitting of the engagement of the filler end of the container C between said heads, and as they are moved toward each other pressing and moving one side wall portion of the container at the filler

opening toward the opposite wall portion to close said filler opening and seal the same. The one head 21 is arranged with a concave face 23 intermediate the ends 24 thereof to conform to the curvature, and of a length substantially the same or slightly greater than the length of, the outer convex portion of the closed container end with the edge 14. The other head 22 has a convex face 25 intermediate the ends 26 thereof in opposed relation to the concave face 23 of the head 21 but being in an arc of a circle having a radius somewhat less than the arcuate face 23 of the head 21 and to correspond with the curvature, and of a length slightly less than the length of the inner concave portion, of the container at the filler end with the arcuate edge 15. The concave face 23 of the head 21 is arranged with a rib 27 and the opposed face 25 of the head 22 is arranged with a correspondingly formed recess 28, whereby as the heads are brought together the closure parts of the opposed portions of the container wall will be offset laterally providing the flute 20 and thereby interlocking the pressed-together closure parts of the container wall. By arranging the arcuate faces 23, 25 of the heads as described the ends of the pressed-together closure parts are pinched or crimped together at the folds with the result that the outer arcuate portion at the edge 14 will exert a force on the inner arcuate portion at the edge 15 to urge and retain said portion in contiguous relation to the opposed arcuate or curved wall portion.

When the container is so formed, the edge portions 14 and 15 lie in stable relation to each other, the inner portion 15 being very slightly shorter than the outer portion. There is thus no force which tends to disrupt the closure seam such as would be present if the inner edge portion were the precise length of the outer edge portion and thus tended to force the filling edge of the container out of its arcuate pressed-together shape. On the other hand, by forcing the inner portion 15 by hand away from the portion 14 a sufficient distance to cause it to assume a position concave to the concave side of the portion 14, the open end of the container will remain in a stable open position convenient for discharging the contents of the container. By merely snapping the wall portion 15 back to the portion 14, the container will again remain closed without the necessity of applying a closure.

To subject the pressed-together closure portions at the filler end to an elevated temperature to render the thermoplastic adhesive material on said surface viscous and cause the same to be bonded together, the heads 21, 22 are heated by suitable means, shown as comprising an electric heating device, shown in a conventional manner at 29 as mounted within the heads.

By the method of closing the filler opening of a container and sealing the closed filler opening in closed condition as described there is provided a single service container wherein the closure parts not only add rigidity to and reinforce the container, and form a particularly strong closed end that will prevent breaking of the seal during handling of the container, but the one closure part will exert a force on the other closure part to urge the parts to and retain them in closed position. Furthermore, the arcuate shape of the closed end of the containers will greatly strengthen the containers for support in an inverted position as described above.

Having described my invention, I claim:

1. As an article of manufacture, a container including a conical body of pliable fibrous material and a closure disk secured in the end of larger 5 diameter of the body and the opposite end constituting the filler opening of the container having a concave edge portion equal to one-half the circumference of the container at said end and an opposed convex edge portion equal to one-half the circumference of the container at said end and closed by engaging the portion having the convex edge with the portion having the concave edge and shaping said engaged portions to arcuate form transversely of the container and 10 15 adhesively secured in said condition.
2. As an article of manufacture, a blank for forming a container body of truncated conical form, comprising a die-cut sheet of quadrilateral form having opposite side edges converging 20 from one end to the opposite end of the blank, the edge of the blank between the diverging ends of the side edges to constitute the base of the container being in the arc of a circle whose center lies in a line extending vertically to said edge 25 midway the side edges of the blank and the opposite edge of the blank between the converging side edges to constitute the filler end of the container arranged with reversely curved arcuate portions extending from the longitudinal center 30 of the blank toward the opposite side edges and being of equal length and of a length substan-

tially equal to one-half the circumference of the container body at the filler end.

3. As an article of manufacture, a blank to form the body of a container having opposite side edges converging from one end to the opposite end of the blank, the edge of the blank between the diverging ends of the side edges to constitute the base of the container being in the arc of a circle whose center lies in a line extending perpendicular to said end midway the side edges, 10 and the edge at the opposite end of the blank between the converging side edges to constitute the filler end of the container arranged with successive reversely curved portions, one curved portion extending from the longitudinal center of 15 the blank toward one side edge and being of concave form and of a length equal to one-half the circumference of the container body at the filler end, the other curved portion of said edge extending from the longitudinal center of the blank 20 toward the opposite side edge and being of convex form and of a length equal to one-half the circumference of the container body at the filler end and adapted to be disposed opposite the concave portion, and said convex portion merging 25 in a concave portion extending to the edge of the blank equal to the width of a marginal portion of the blank to be lapped over the marginal portion at the opposite side of the blank when the blank is shaped to container body form. 30

HENRY T. SCOTT.
